F. FERRARA

WINDOW SHADE ROLL AND HOLDER THEREFOR

Filed Nov. 20, 1923

UNITED STATES PATENT OFFICE.

FRANCESCO FERRARA, OF SOMERVILLE, MASSACHUSETTS.

WINDOW-SHADE ROLL AND HOLDER THEREFOR.

Application filed November 20, 1923. Serial No. 675,825.

To all whom it may concern:

Be it known that I, FRANCESCO FERRARA, a citizen of the United States, residing at Somerville, in the county of Middlesex and State of Massachusetts, have invented new and useful Improvements in Window-Shade Rolls and Holders Therefor, of which the following is a specification.

This invention relates to a window shade roll and holders therefor, and has for its object to provide an improved means for supporting an ordinary spring actuated window shade roll, said supporting means comprising two separate holders, one of said holders being adapted to be attached to the journal pin which is fast to the window shade roll, the other of said holders being adapted to be attached to the spindle to which the spring which rotates the roll is attached and said holders each have a cord fastened thereto which extends upwardly therefrom and through suitable guides which are fastened to the window casing in such a manner that the roll with a shade thereon may be raised and lowered bodily so that the shade may be used to cover any desired portion of the upper or lower window sash or both of said sashes, thus making it possible to open the window at the top or at the bottom, or at both top and bottom and still have the shade cover that portion of the sashes located between the open spaces.

It is still further an object of the invention to so construct the holders for the window shade roll that said holders may be rigidly fastened in different positions and at different locations upon the window frame if it is so desired.

40 The invention consists in the combination and arrangement of parts set forth in the following specification and particularly pointed out in the claims.

Referring to the drawings:

45 Figure 1 is a front elevation of my improved window shade roll and holders therefor, the same being shown suspended on cords and in connection with a window casing and sash.

50 Fig. 2 is a side elevation of the holder in which the spring spindle is mounted, said holder being viewed from the left hand side of Fig. 1.

55 Fig. 3 is a front elevation of the spindle holder.

Fig. 4 is also a front elevation of the spindle holder, the same being illustrated rigidly fastened to the side of the window casing.

Fig. 5 is a side elevation of the spindle holder, the same being illustrated rigidly fastened to the front of a window casing.

Fig. 6 is a view of the opposite side of the spindle holder from that illustrated in Fig. 5.

Fig. 7 is a side elevation of the spindle clamp.

Fig. 8 is a front elevation of the holder in which the journal pin of the window shade roll is mounted.

Fig. 9 is a side elevation of the holder illustrated in Fig. 8.

Like numerals refer to like parts throughout the several views of the drawings.

In the drawings, 10 is a window casing, 11 a window sash, 12 a window shade roll and 13 a window shade mounted upon said roll. The window shade roll 12 is mounted at one end thereof in a spindle holder 14 and at the other end thereof in a journal pin holder 15 and said holders have cords 16 and 17 respectively fastened thereto which extend upwardly therefrom and through guides 18 and 19 respectively fastened to the window casing 10 and from thence over a pulley 20 also fast to the window casing 10 and to a cleat 21 where they may be secured in any suitable manner.

A spindle 22 of well known construction and provided with the usual flattened outer end projects a short distance from one end of the window shade roll 12, while at the other end of said roll a journal pin 23 also of well known construction projects. The pin 23 is provided with the usual flange 24.

The spindle holder 14 is preferably constructed of sheet metal and consists of a flat side portion 25 at one end of which a flange 26 is formed, said flange preferably being bent perpendicular to the flat portion 25. At its other end the holder 14 is bent to form a U-shaped portion 27. The flat portion 25 of the holder 14 has a slot 28 formed therein, a portion 29 of said slot extending inwardly from the edge of said holder and terminating with a portion 30 which is located at right angles to the portion 29. Another slot 31 is formed in the U-shaped portion 27 of said holder, said slot 31 being oppositely disposed to and aligning with

110

the portion 30 of the slot 28. Holes 32 are formed in the flange 26 and when the holder 14 is utilized as illustrated in Figs. 1, 2 and 3, the cord 16 is secured to the holder 14 by 5 being passed through said holes, after which a knot is formed in the end of said cord. The holes 32 may also be utilized in securing the holder 14 to the under side of the window casing by screws 33 as illustrated 10 in Fig. 4, or to the front surface of the window casing 14 by screws 34 as illustrated in Figs. 5 and 6. Other holes 35 are also formed in the side 25 of the holder 14, said holes being utilized when it is desired to 15 secure said holder to the side of the window casing 14 by screws 36 as illustrated in Fig. 4.

Mounted upon the holder 14 and preferably located within the U-shaped portion 20 thereof is a clamping member 37. The member 37 is preferably constructed of a single piece of sheet metal and is pivotally mounted at 38 upon the side 25 of said holder. The clamping member 37 illustrated in detail in Fig. 7, embodies therein a flat portion 39, one edge portion of which is bent to form a flange 40, said flange being perpendicular to the flat portion 39 and a portion of the material comprising said 25 flange 40 is in turn bent to form a clamp arm 41, the latter being parallel to the flange 40, and the space between the flange 40 and clamp arm 41 constitutes a clamping space 42 in which the flattened end of 30 the spindle 22 may be inserted. A bolt 43 extends between the flange 40 and clamp arm 41 and is utilized to secure said spindle 22 in said clamping member. A slot 44 is provided in the flat portion 39 of the clamping member 37 and said slot is so located that when the clamping member is positioned as illustrated in Figs. 5 and 6, that it will align with the portion 29 of the slot 28 in the holder 14.

45 The journal pin holder 15 is quite similar in construction to the holder 14 and consists of a flat side portion 45 at one end of which a flange 46 is formed, said flange preferably being bent perpendicular to the flat portion 45. At its other end the holder 15 is bent to form a U-shaped portion 47. The flat portion 45 of the holder 15 has a slot 48 formed therein, the upper portion of said slot being larger than the lower portion 50 thereof in order that the flange 24 of the pin 23 may be inserted therethrough and formed in the U-shaped portion of the holder 15 is a hole 49 which aligns with the lower portion of the slot 48 and said hole 49 and the lower end of the slot 48 constitute a journal in which the pin 23 may rotate. The flange 46 of the holder 15 is provided with holes 50 through which the cord 17 is inserted in securing said cord to said 60 holder and said holder is also provided with 65

other holes 51 which may be utilized in securing said holder to the side of a window casing.

The general operation of the device hereinbefore specifically described is as follows:—When it is desired to utilize the window shade as illustrated in Fig. 1, the holder 14 is attached to the spindle 22 and held securely thereon through the medium of the clamping member 37. Upon such occasions the flattened end of the spindle 22 projects through the portion 30 of the slot 28 of the holder 14 and into the clamping space 42 formed between the flange 40 and clamp arm 41 of said clamping member 37 and said flattened end is secured in said clamping member through the medium of the bolt 43. At the other end of the window shade roll 12 the holder 15 is secured to the journal pin 23 by inserting said pin through the slot 48 and hole 49 in said holder. The cords 16 and 17 attached to their respective holders are then inserted through the guides 18 and 19 and pulley 20 and said cords are then utilized in raising and lowering the window shade bodily as desired and the cords are then fastened to the cleat 21. The window shade 13 may then be unrolled from the window shade roll 12 in the usual well known manner.

When it is desired to fasten the holders 14 and 15 rigidly at various locations upon the window casing 10, the flanges 26 and 46 respectively of said holders are utilized in securing said holders to said casing and upon such occasions, the flattened end of the spindle 22 is located either in the portion 29 of the slot 28 or in the slot 31 as the case may be. No matter in what position the holder 15 is secured to the window casing 10, the journal pin 23 is always located in the hole 49. When the holder 14 is rigidly fastened to the window casing it is not necessary to utilize the clamping member 37 in securing the spindle 22 in said holder.

I claim:

1. In combination, a spring actuated window shade roll, a spindle projecting from one end of said roll, said spindle being provided with a flattened outer end, a holder embodying therein a flange at one end thereof whereby said holder may be rigidly secured to a stationary support, and a U-shaped portion at the other end thereof and having a slot formed therein through which said spindle projects, a clamping member pivotally mounted upon said holder within said U-shaped portion and means to grip said flattened end of said spindle in said member.

2. In combination, a spring actuated window shade roll, a spindle projecting from one end of said roll, said spindle being provided with a flattened outer end, a holder embodying therein a U-shaped portion and

having a slot formed therein through which said spindle projects, a clamping member pivotally mounted upon said holder within said U-shaped portion and embodying there- 5
• in a clamping space, said clamping member being adapted to be rocked to position said clamping space into and out of alignment with said slot and means to grip said flattened end of said spindle within said clamp- 10
ing space.

3. In combination, a spring actuated wind- 15
dow shade roll, a spindle projecting from one end of said roll, said spindle being pro-
vided with a flattened outer end, a holder
embodying therein a flange whereby said holder may be rigidly secured to a stationary support and a U-shaped portion, the latter having a pair of oppositely disposed slots

formed therein adapted to receive said spindle, a clamping member pivotally mounted upon said holder within said U-shaped portion and embodying therein a slot and a clamping space, said clamping member being adapted to be rocked to position the slot and clamping space thereof into and out of alignment with the slots of said holder and means to grip said flattened end of said spindle within said clamping space. 20
25

In testimony whereof I have hereunto set my hand in presence of two subscribing wit- 30
nesses.

FRANCESCO FERRARA.
